UNITED STATES PATENT OFFICE.

ANDREW N. POLYMATH, OF LOS ANGELES, CALIFORNIA.

PICTURE.

SPECIFICATION forming part of Letters Patent No. 643,275, dated February 13, 1900.

Application filed January 27, 1899. Serial No. 703,603. (No model.)

To all whom it may concern:

Be it known that I, ANDREW N. POLYMATH, a citizen of the United States, residing in the city and county of Los Angeles, in the State 5 of California, have invented certain new and useful Improvements in Pictures, of which the following is a specification.

This invention relates to certain new and useful improvements in pictures, having for 10 its principal object to produce a picture bearing close similarity to an original oil or water-color painting and one in which the colors will not fade or be affected by the atmosphere or the materials used in producing the picture.

15 With this object in view the invention consists in the improved pictures hereinafter more particularly described.

In the accompanying drawings, wherein the invention is illustrated conventionally, Figure 1 is a front view showing different layers of material cut away at one corner; and Fig. 2 is an edge view showing portions of the completed picture, the parts being enlarged for sake of clearness.

25 In carrying out the invention any ordinary picture printed upon any suitable material capable of being rendered transparent—say, for instance, an ordinary photographic print *a*—is either soaked or rubbed gently with a 30 solution to render it transparent, Lucca oil being preferably employed for this purpose, as in practice it has been found very desirable.

All surplus oil is then removed from the opposite surfaces of the picture, and the same 35 is thoroughly dried, after which the desired colors *b* are applied to the back thereof, and by reason of the transparency of the original picture the said colors are plainly visible through the same and give the picture every 40 appearance of being an original painting.

After the colors have been applied to the back of the picture they are permitted to dry, and then a coating or layer of opaque waterproof material *c* is applied thereto, white paint being suitable for this purpose. The opaque 45 waterproof coating being allowed to dry, the picture is affixed to a suitable backing *e*, canvas being preferred, by means of a suitable adhesive material *d*. A suitable material for 50 this purpose and one which in practice has proved very effective consists of one ounce

each of corn-starch and flour added to one pint of water, to which is added ten grains of tragacanth dissolved in hot water. This mixture is allowed to boil until it attains the 55 desired thickness for pasting.

When canvas is used as a backing and the picture is pressed into firm contact therewith, it conforms to the grain or roughened surface of the canvas and has every appearance of 60 having been painted thereon originally.

I am aware that heretofore it has been proposed to color pictures by first rendering the same transparent, then applying the desired colors to the back thereof, and finally affixing the same by means of glue or other adhesive material to a backing. I am not aware, however, that it has ever been proposed to protect the colors after they have been applied by means of an opaque waterproof coating. 70 Such a coating not only adds brilliancy to the colors, protects them from being affected by the atmosphere, but, in addition, prevents them coming into contact with the adhesive material.

It has been found in practice that where some oil-colors are brought directly into contact with an adhesive material they lose their true color and often become cloudy in appearance. This objection, however, is entirely 80 overcome by forming pictures according to the hereinbefore-described method.

Having thus fully described my invention, what I claim, and desire to secure by Letters Patent, is—

85 As a new article of manufacture, a picture comprising a transparent photograph, engraving or the like, a layer of colored paints upon the back of said photograph, a coating of opaque waterproof material upon the paints, 90 a suitable backing and a layer of adhesive material interposed between the waterproof material and the backing, substantially as described.

In testimony whereof I have signed my 95 name to this specification in the presence of two subscribing witnesses.

ANDREW N. POLYMATH.
